UNITED STATES PATENT OFFICE.

ISIDOR LASSNER, OF NEW YORK, N. Y.

DESIGN FOR A NECKLACE.

Application filed June 11, 1915. Serial No. 13,741. Term of patent 3½ years.

To all whom it may concern:

Be it known that I, ISIDOR LASSNER, a citizen of the United States of America, residing at New York city, county and State of New York, having invented a new, original, and ornamental Design for a Necklace, of which the following is a specification, reference being had to the accompanying drawing, forming part hereof, which illustrates a front elevation of a necklace showing my new design.

I claim:

The ornamental design for a necklace as shown.

Signed at New York city, New York, this 4th day of June, 1925.

ISIDOR LASSNER.
